UNITED STATES PATENT OFFICE

116,749

DESIGN FOR A VEGETABLE CUTTER

Adolph P. Osius, Detroit, Mich.

Application July 5, 1938, Serial No. 78,258

Term of patent 3½ years

To all whom it may concern:

Be it known that I, Adolph P. Osius, a citizen of the United States, residing at Detroit, in the county of Wayne and State of Michigan, have invented a new, original, and ornamental Design for Vegetable Cutters, of which the following is a specification, reference being had to the accompanying drawing, forming part thereof.

Fig. 1 is a front elevational view of a vegetable cutter;

Fig. 2 is a side elevational view thereof, and Fig. 3 is a perspective view, showing my new design.

I claim:

The ornamental design for a vegetable cutter, as shown.

ADOLPH P. OSIUS.
